PROCESS FOR THE CONTINUOUS REFINING OF LENGTHS OF TEXTILE MATERIALS AND THE LIKE

Christian A. Meier-Windhorst, Hamburg, Germany, assignor to Artos Dr. Ing. Meier-Windhorst K.G., Hamburg, Germany

No Drawing. Filed Dec. 9, 1965, Ser. No. 512,771
4 Claims. (Cl. 8—101)

ABSTRACT OF THE DISCLOSURE

A length of textile material which is being refined by continuous impregnation with a suitable refining medium, is maintained in an atmosphere consisting of a mixture of steam and an inert gas in order to provide the real treating temperature of the refining process, said temperature being below 100° C.

This invention relates to a process for a continuous refining treatment of lengths of textiles of all types in connection with bleaching, dyeing, pressure after-treatment and high-refining with heat treatments while excluding air-oxygen.

Heretofore continuous heat treatments with the exclusion of air-oxygen took place during bleaching and dyeing, during pressure after-treatment of the wet impregnated textiles in the two-phase process and during pressure after-treatment of textiles dried after the pressure treatment in the Rongalith-potash process in pure steam, i.e., at temperatures of 100° C. and higher.

Some bleaching and drying processes can not be carried out under temperatures of 100° C., either due to the chemicals which are being used or due to the nature of the wet materials which are susceptible to such temperatures. In that case operation takes place in a steam-air mixture and the drawbacks of the presence of a certain percentage of air-oxygen must be accepted. Usually in those cases compromises are effected between the drawbacks of the higher temperature and those of the present oxygen content.

The reduction dyeing process, for example, the dyeing with vat dyes, does not permit the presence of even a few percentages of air-oxygen, so that up to now it was necessary to operate in pure steam and thus with treating temperatures of 100° C.

An object of the present invention is the development of a continuous or semi-continuous process for the main textile refining treatment which permits at all times the use of temperatures for treated materials which are below 100° C. and preferably between 50 and 90° C., and which operates under normal pressure but with the exclusion of air-oxygen.

Other objects of the present invention will become apparent in the course of the following specification.

In the accomplishment of the objectives of the present invention it was found desirable to provide a process for a continuous refining treatment of lengths of textile materials of all types, wherein the length of textile material which is continuously impregnated with a treating medium, is introduced into a heat treating chamber which is filled uniformly with a mixture of steam and an inert gas, such as nitrogen, the ratio of the mixture being

2

such that the actual saturation temperature of the partial pressure of steam corresponds to the real treating temperature of the refining process.

Preferably, a mixture of steam and inert gas is continuously introduced into the heat treating chamber, whereby the desired partial steam pressure is preferably maintained by suitably varying the amount of the inert gas by measuring the temperature indicated by a wet bulb thermometer close to the inlet of the length of material.

It was also found advisable to conduct a certain excessive amount of the mixture of steam and inert gas in countercurrent over a heating zone for the material which is located close to the inlet of the material.

The excessive amount of the mixture of steam and inert gas should leave the treating chamber or the heating zone through a very narrow inlet slit or, when the material continuously passes through the treating chamber, through an equally narrow outlet slit, whereby the actual flow resistance in the treating chamber produces a slight excess pressure which prevents uncontrolled penetration of air and, consequently, of oxygen.

To diminish consumption of inert gas the length of material can be introduced into the treating chamber through a special seal serving slit and also, preferably, withdrawn through such a slit.

It was found that a dyeing process following the present invention completely eliminates many difficulties heretofore encountered in bleaching, formation of sodium cellulose, and in dyeing with vat dyes, for example when dyeing close mercerized poplins.

It is apparent that the described invention is subject to many variations and modifications within the scope of the appended claims.

What is claimed is:

1. In a refining heat treating process wherein a length of textile material is being impregnated with a liquid at a temperature below 100° C. and at atmospheric pressure, the step of introducing said length of textile material into a chamber filled with a mixture of steam and an inert gas, in order to attain the real treating temperature.

2. A process in accordance with claim 1, wherein the inert gas is nitrogen.

3. A process in accordance with claim 1, comprising the further step of adjusting the ratio of the mixture by varying the amount of the inert gas until the actual saturation temperature of the partial pressure of steam corresponds to the real treating temperature of the heat treating process.

4. A process in accordance with claim 1, wherein said chamber has a heating zone for said length of textile material close to the inlet thereof into said chamber, and wherein said mixture is conducted to said length of textile material over said heating zone in countercurrent to the direction of movement of said length of textile material.
